Primary Examiner — Ian Simmons*Assistant Examiner* — Yolanda Robinson(74) *Attorney, Agent, or Firm* — Young & Thompson(57) **CLAIM**

The ornamental design for an operating grip for endoscope, as shown and described.

DESCRIPTION

FIG. 1 is a top, front and left side perspective view of an operating grip for endoscope showing a first embodiment of my new design;

FIG. 2 is a bottom, front and left side perspective view thereof;

FIG. 3 is a front elevational view thereof;

FIG. 4 is a rear elevational view thereof;

FIG. 5 is a top plan view thereof;

FIG. 6 is a bottom plan view thereof;

FIG. 7 is a left side elevational view thereof; and,

FIG. 8 is a right side elevational view thereof.

The broken line portions of the operating grip for endoscope throughout the drawings are shown to illustrate environment only and form no part of the claimed design.
